RALPH S. KELSO, OF CLEVELAND, OHIO, ASSIGNOR TO THE STANDARD SEWING MACHINE COMPANY, OF CLEVELAND, OHIO, A CORPORATION OF OHIO.

TRIMMING MECHANISM FOR SEWING-MACHINES.

1,129,403.

Specification of Letters Patent. Patented Feb. 23, 1915.

Application filed June 30, 1911. Serial No. 636,138.

To all whom it may concern:

Be it known that I, RALPH S. KELSO, citizen of the United States, and resident of Cleveland, in the county of Cuyahoga and State of Ohio, have invented certain new and useful Improvements in Trimming Mechanism for Sewing-Machines, of which the following is a specification.

This invention relates to a trimming mechanism for sewing machines, and particularly to a trimming mechanism of the type designed for trimming or cutting the free edge of the undermost of two or more plies of material that have been, or are being, sewed together, as for example, in the case of the inner ply or lining piece of a shoe top to which piece is sewed an outer piece folded or doubled to form two plies.

The principal object of the present invention is to provide an improved trimming mechanism of this general type in which the cutting-blade, or movable trimming-knife, generally employed for severing the surplus stock from the free edge of the under ply is moved in a path which, though in a general way oblique or diagonal to the line of stitching, is not a right line but is a curved line preferably following the arc of the diagonal chord in which the movable knives of edge-trimming mechanisms as heretofore constructed have generally been operated. In the previous edge-trimming mechanisms in which the movable trimming-knife operated in this straight line, diagonal or oblique to the line of stitching, the under ply of the work was cut off by a diagonal cut at one side of the line of stitching which cut was within the edge of the single or doubled upper piece of material. In practice, however, it was found somewhat difficult to trim off the edge of the lower ply as close to the line of stitching as desired, and it was also somewhat difficult to avoid the danger of cutting some of the stitches, especially if the under ply was trimmed quite closely.

The principal feature which distinguishes the action of the present movable trimming-knife from that of the knives heretofore employed is that by moving the knife in a curvilinear path, and especially in a path which follows substantially the arc of the chord in which the knives of the older trimming mechanisms were operated, it is feasible to trim material closer to the line of stitching than with a knife movable in such

a straight diagonal line or chord and with considerably less danger of cutting into the row of stitching.

Another important feature of the invention is the provision of means for operating this movable trimming-knife regularly in its arc, in such a manner as to give a powerful but substantially noiseless movement of the trimming mechanism at any speed within the capacity of the stitching mechanism. This is accomplished preferably by operating the movable trimming-knife from an eccentric secured to the main upper shaft located in the sewing machine head.

Suitable work pressing and gaging means constitute important elements of any mechanism for trimming the edge of the lower ply of a plurality of plies of material that are being sewed together. The gaging and pressing means forming part of this invention present various features of novelty, one of which is the association of these two means in such a manner that in the normal operation of the machine the gaging means will rise and fall substantially in unison with the presser, though mounted independently of the presser and capable of independent movement relative to it when it is desired to throw the gage into or out of action.

Other features of the invention not hereinbefore referred to will be hereinafter described and claimed, and are illustrated in the accompanying drawings, in which—

Figure 1 is an elevation of the front side of a portion of the head of a sewing machine, illustrating the present invention applied thereto, only so much of the sewing machine being shown as is necessary for illustration of the invention. Fig. 2 is an elevation of the front end of the machine, with the cover-plate removed to show the mechanism more clearly and with the presser-roller swung to its inoperative position. Fig. 3 is an elevation of the rear side of the mechanism shown in Fig. 1. Fig. 4 is a sectional, rear end elevation of the same, the section being taken in line 4—4, Fig. 3, and looking in the direction of the arrows. Fig. 5 is a side elevation, similar to Fig. 1, showing the parts in different positions, to illustrate particularly the positions of the presser and edge-gage when the presser is raised from the work. Fig. 6 is an enlarged, sectional perspective of a portion of

the operating connections to the movable trimming-knife, and illustrates also the mechanism for throwing said knife into and out of action. Figs. 7 and 8 are details 5 illustrating the edge-gage and the means for throwing it into and out of action and for holding it out of action. Fig. 9 is a detail illustrating the relative positions of the presser, the needle and the movable trimming-knife when the knife is in lowered or 10 cutting position. Figs. 10 and 11 are respectively an under side view, and a vertical section taken in line 11—11 of Fig. 10, of the needle-plate and co-operative parts, 15 illustrating the manner in which the movable trimming-knife is held against the fixed trimming-knife at the needle-plate and the opening for the movable knife closed and opened as required.

20 Similar characters designate like parts in all the figures of the drawings.

Many of the parts of the machine illustrated are or may be the same or substantially the same as those of well-known types 25 of sewing machines as heretofore constructed. The drawings show so much of one well-known type of sewing machine as is deemed necessary to illustrate the invention, the other parts of said machine being 30 of the usual construction in that type of sewing machine, but not immediately associated with the elements in which the present invention mainly resides. Among the parts illustrated of well-known construction, 35 and for which other specifically different parts having corresponding functions may readily be substituted, are the overhanging arm 2, with its head 3, in which are mounted for vertical reciprocation a needle-bar 4 carrying an eye-pointed needle 5, a presser-bar 6 carrying a suitable presser, preferably a roller-presser 7, a tension device 8, a take-up 12, and a main upper shaft 9 from which the movements of the needle-bar and various 40 other parts are derived. The usual crankpin 10 and connecting pitman 11 are shown for operating and controlling the movement of the needle-bar and needle; also the usual lever 13 for raising and lowering the presser 45 and presser-bar, said lever serving also to operate a lever 14 for simultaneously releasing or applying tension to the needle-thread. Below the operating parts just referred to are also the usual bed-plate 15 and the needle-plate 16 with its needle-opening. 50

Various other parts of well-known construction and function are also illustrated, but it is deemed unnecessary to describe them specifically herein.

60 As before stated the principal feature of the edge-trimming mechanism of the present machine is a movable trimming-knife or cutter operating in a curvilinear path, which 65 is preferably substantially the arc of a chord in which such knives as heretofore used

have been operated. The movable knife or cutter itself may be of substantially the same construction at its lower cutting end as knives of this character heretofore used and is illustrated at 17. At its upper end it is 70 slotted or forked, as indicated at 18, to provide for its vertical adjustment with respect to its carrier. The knife-carrier used in the present machine, designated generally by 75 19, is preferably one having a movement in a curvilinear path, and as shown it is mounted to oscillate about a pivot p distant from the path of movement of the needle and the line of stitching, the center of oscillation being considerably to the left of the 80 needle. The knife-carrier as illustrated embodies as its main element a long-armed lever 20, which is pivoted in this case on a bracket-arm 21, fastened to the under side of the head and surrounding a sleeve or 85 bearing 22, in which the presser-bar reciprocates.

An important feature of this improved mechanism is the provision of means for 90 operating the knife carrier in a curvilinear path. The operating element is here shown as a knife-bar 23, similar to the needle-bar and presser-bar so far as its general construction and mode of operation are concerned, it being mounted for vertical reciprocation in the head of the machine, as most clearly shown in Fig. 6. At the point of connection of the knife-bar 23 and the lever 20 a pin-and-slot connection 26 is illustrated 95 for permitting the lever to swing properly 100 in its arc when actuated by the knife-bar. The movable trimming-knife 17 is not mounted directly on the main element or lever 20 of the knife-carrier 19, but instead is mounted on a lower extension 24 of said 105 lever arm in such a manner as to have, in addition to the curvilinear movement imparted to it by said lever, another curvilinear or swinging movement about its own axis on said lever, this axis being in the 110 present construction on a short lever 27, mounted on said extension 24, of the lever-arm 20, preferably substantially in line with the axis of the knife-bar. The movable trimming-knife 17 is here shown as adjustably secured directly to this short lever 115 27 at the axis of oscillation of the same. Thus the free or right-hand end of the short lever 27 is capable of moving relatively to the corresponding end 25 of the main lever 120 20. These two ends of said levers are represented in the drawings as connected together, the connection being a short post or guide-pin 28 pivoted to the free end of the lever 27 and passing through an opening 125 in the corresponding end 25 of the lever 20. A spring 29 is coiled about this rod and interposed between the ends of these two levers, its function being to yieldingly hold the knife in position for close coöperation 130

with the stationary cutter on the needle-plate. For instance, when the parts are in the positions shown in Fig. 1, with the knife in lowered cutting position, the main lever 5 20 serves to compress said spring and so cause the knife to closely coact with the stationary cutter, while in Fig. 5, where the knife is shown in raised position, this pressure is shown as relieved. An adjusting 10 nut is shown at 30 for regulating the distance between the ends of these levers and consequently the tension of the spring 29.

To the parts just described as constituting the principal elements of the mechanism 15 for moving the trimming-knife 17 in a curvilinear path, motion is preferably transmitted by an eccentric 31 on the main upper shaft 9 of the machine, and suitable connections between the eccentric and the knife-bar. 20 23. The connections shown comprise an eccentric rod 32, the free end of which is pivoted to and adjustably connected with a rocker-arm 33 supported by a bracket 33' on the machine arm, (see Figs. 3 and 4), which 25 rocker-arm is in turn pivotally and preferably adjustably connected with an angle-lever 34, the long arm of which is substantially vertical and the short arm of which is substantially horizontal and may be connected with and disconnected from the knife-bar at will. By means of a throw-in-and-out device this angle-lever 34 may be operatively connected to or disconnected from the knife-bar. When these parts are operatively 30 connected, the knife-bar will, of course, be reciprocated vertically in its bearings and the knife-carrier will be oscillated to operate the knife 17 in the manner hereinbefore described, but by disconnecting said parts the 35 knife-bar will remain inactive and the machine may be used for ordinary sewing only. Said throw-in-and-out device as here shown embodies a spring-pressed pin 35 working in a post extending outward laterally from the 40 end of the short arm of the angle-lever 34, said pin extending into a recess 36 located in a block 37 secured to the upper end of the knife-bar (see Fig. 6). It will be evident that, by merely giving the head 38 of the 45 pin 35 a pull, the knife-bar will be disconnected from the operating mechanism. When so disconnected it may be raised automatically from the work and held out of action until it is desired to make use of it again. Any suitable means may be employed for raising the movable trimming-knife and knife-bar in this manner, the 50 means shown being a spring 39 coiled about a pin 40, which may be carried by the block 37 and may work in an opening in the lower end of the head of the machine, as shown in Fig. 6. The spring 39 when the parts are 55 disconnected, exerts its pressure upwardly to raise the trimming mechanism as just described. After the parts have been discon-

nected and it is desired to reconnect them again, it is merely necessary to pull down the knife-carrier, when the pin will snap back again into the open side of the recess 36 and thus lock the knife-bar to its operating lever. 70

In connection with the edge-trimming knife and its operating mechanism just described it is customary to employ suitable pressing means for engaging the work close to the line of stitching. In the present case the preferred construction is a roller-presser of the type described in detail and claimed in a companion application, Serial Number 636,139, filed June 30, 1911. The main features of this part of the machine are the roller-presser 7 and suitable means for adjusting it in two intersecting paths, preferably in a horizontal plane, and for also moving it into and out of an operative position, the construction being such that when the roller-presser is moved to its inoperative position it is located at a considerable distance from the needle and the knife 17 as shown in Fig. 2, and 80 the operator has ready access to the needle for threading it and to the knife for adjusting it, etc. Here said roller-presser is shown as pivotally mounted at the end of an adjustable arm 41 of a lever 42, pivoted 85 on a horizontally adjustable member or carrier 43, secured to a block 44, fastened to the lower end of the presser-bar 6. The construction of these parts is such that the carrier 43 is adjustable horizontally on the 90 block 44 in a path transverse to the line of stitching, while the arm 41 of the lever 42 is adjustable in a path substantially parallel with the line of stitching. The result is that with these two adjustments the roller-presser 100 can be brought closer to, or moved farther away from, the line of stitching, as desired, and may be moved so that its point of contact with the work is either in front of, in the rear of, or substantially coincident with, 105 the line of movement of the needle, as desired. In all the adjustments of the roller-presser, however, it may be swung about a pivot or hinge 45 from an operative to an inoperative position and vice versa. When 110 in operative position it is between the upper and lower walls of a guideway 46, formed in the carrier 43, which serve to take all the strain of the mechanism off the hinge 45. In said operative position the lever may also 115 be locked in place normally, as by means of a locking spring 47, which is shown as U-shaped. Of course this roller-presser is raised from or engaged with the work according as the presser-bar is moved up or 120 down by the action of the lever 13. 125

Associated with the trimming-knife 17 and the roller-presser is also shown an edge-gage which may be of the type illustrated at 48. The working portion of the gage 130

proper of this edge-gage is here illustrated as an extension of a spindle 49, mounted in a long bearing 50 which in the present construction is adjustably secured to the main bracket-arm 21, carrying the trimming mechanism. Here the bracket-arm is illustrated as having an open-sided clamp 51, formed as part of the bracket-arm and so constructed as to permit the gage-carrier—that is, the sleeve of the spindle—to be located in an inclined or diagonal position with respect to the line of stitching. The spindle 49 has a stop 52, between which and the lower end of the bearing 50 is shown a spring 53, which normally holds the edge-gage down and in working position. At the upper end of said sleeve is shown a lateral arm 54 with which coöperates a detent device 55, carried by the upper end of the spindle 49. This detent may be of any suitable construction, one simple form being illustrated clearly in Figs. 7 and 8. By means of the latch-arm 56 of this detent device the spindle may be latched in its uppermost position, shown in said figures, or released, when it will be drawn down by the spring 53 to the full line position shown in Fig. 7. This control of the throwing in and out of the edge-gage is entirely independent of any control by the other mechanism. An important feature of the mechanism, however, is the provision of means for controlling the throwing out of action of the edge-gage directly from the pressing means. It is desirable to raise the edge-gage at the same time that the roller-presser is raised, and in order to accomplish this result there is illustrated at 57 an upwardly extending arm secured to the block 44, which arm has at its extreme upper end a finger that projects under the main portion of the detent device 55 and engages the under side of it at a point close to the spindle 49. Thus it will be clear that, whenever the lever 13 is actuated to raise the presser-bar and presser, the edge-gage will also be raised simultaneously with the presser mechanism by the action of the arm 57, which engages and lifts the detent 55 and with it the edge-gage. The relative positions of these parts when in contact with the work and when raised away from the work is shown clearly in Figs. 5 and 7.

The construction and mode of operation of all the new features of the mechanism above the bed-plate of the machine have now been fully described. It remains only to point out briefly the parts at the needle-plate which coöperate with the movable trimming-knife, the needle, and the edge-gage. Referring to Figs. 10 and 11 it will be seen that the movable trimming-knife 17 has at its lower end the usual extension or guide-finger 58 which works in an opening in the needle-plate adjacent to the needle and needle-open-

ing which knife-opening has as one wall thereof the fixed trimming-knife or cutter 59, which coöperates directly with the movable knife 17 and has a beveled surface for coöperation therewith as shown. The other wall of this opening is movable and the width of the opening itself is variable, it varying with the position of the movable knife 17 as the latter is moved up and down in its curvilinear path. The movable wall of this opening is here shown at 60, at the edge of a movable plate 61, mounted to work in a guide-way cut in the needle-plate adjacent to the fixed trimming-knife or cutter 59. It will be understood that this movable plate will normally be pressed, as by means of a spring 62, toward the fixed edge of the cutter 59, in order to keep the opening through which the knife passes closed at all times.

What I claim is:—

1. In a trimming mechanism for sewing machines provided with a needle-plate, the combination with a fixed trimming knife associated with the needle-plate, of a co-operating movable trimming knife, and mechanical means above the needle-plate for actuating said movable trimming-knife in a curvilinear path. 85

2. In a trimming mechanism for sewing machines provided with a needle-plate, the combination with a fixed trimming-knife associated with the needle-plate, of a co-operating movable trimming-knife, and mechanical means above the needle plate for actuating said movable trimming-knife in an arc the chord of which is diagonal to the thickness of the material. 95

3. In a trimming mechanism for sewing machines, the combination with a fixed trimming-knife, of a vertically reciprocatory knife-bar, a movable trimming-knife, and connecting means between said knife-bar and the movable trimming-knife for converting the rectilinear movement of said knife-bar into a curvilinear movement of said movable trimming-knife. 105

4. In a trimming mechanism for sewing machines provided with a needle-plate, the combination with a fixed trimming-knife associated with the needle-plate, of a pivoted knife-carrier, a trimming-knife connected with said knife-carrier, and mechanical means above the needle plate for oscillating said knife-carrier. 115

5. In a trimming mechanism for sewing machines provided with a needle-plate, the combination with a fixed trimming-knife associated with the needle-plate, of a vertically reciprocatory knife-bar, a pivoted knife-carrier, a trimming-knife connected with said knife-carrier, and connecting means between the said knife-bar and knife-carrier for converting the rectilinear movement of the knife-bar into a curvilinear movement of the movable trimming knife. 120 125

6. In a trimming mechanism for sewing machines provided with a needle-plate, the combination with a fixed trimming-knife associated with the needle-plate, of a knife-carrier pivoted at one side of the line of stitching, a movable trimming-knife pivotally supported by said knife-carrier, means to yieldingly hold said movable knife in proper position to coöperate with said fixed 60
5 knife, and mechanical means above the needle-plate for oscillating said knife-carrier and movable trimming-knife about their respective pivots.
7. In a trimming mechanism for sewing machines provided with a needle-plate, the combination with a fixed trimming-knife associated with the needle-plate, of a knife-carrier pivoted to a stationary support at one side of the line of stitching, a movable 65
10 trimming-knife connected with said knife-carrier, mechanical means above the needle-plate for oscillating said knife-carrier, and a spring holding said movable knife in position for coöperation with the fixed knife.
- 20 8. In a trimming mechanism for sewing machines provided with a needle-plate, the combination with a fixed trimming-knife associated with the needle-plate, of a movable trimming-knife, and mechanical means 70
25 above the needle-plate for actuating said movable trimming-knife between an operative position and an inoperative position in which it is located considerably above and at one side of the vertical plane of the line of stitching, said movement being in a curvilinear path gradually approaching said line of stitching.
- 30 9. In a trimming mechanism for sewing machines provided with a needle-plate, the combination with a fixed trimming-knife associated with the needle-plate, of a rotary shaft, an eccentric on said shaft, a movable trimming-knife, and connecting means between said eccentric and said movable knife 75
35 for actuating the latter in a regular manner in a curvilinear path gradually approaching the line of stitching.
- 40 10. In a trimming mechanism for sewing machines provided with a needle-plate, the combination with a fixed trimming-knife associated with the needle-plate, of a rotary shaft, an eccentric on said shaft, a vertically reciprocating knife-bar operated by said eccentric, a pivoted knife-carrier, a movable trimming-knife connected with said knife-carrier, and connecting means between said 80
45 knife-carrier and knife-bar for actuating the latter in a curvilinear path, and a throw-out device for disconnecting said knife-bar from said eccentric.
- 50 11. In a trimming mechanism for sewing machines provided with a needle-plate, the combination with a fixed trimming-knife associated with the needle-plate, of a rotary shaft, an eccentric on said shaft, a vertically reciprocating knife-bar operated by said eccentric, a pivoted knife-carrier, a movable trimming-knife pivotally supported by said knife-carrier, and connecting means between said knife-bar and knife-carrier for oscillating 85
55 said knife-carrier and trimming-knife about their respective pivots.
- 60 12. In a trimming mechanism for sewing machines provided with a needle-plate, the combination with a fixed trimming-knife associated with the needle-plate, of a rotary shaft, an eccentric on said shaft, a vertically reciprocating knife-bar operated by said eccentric, a movable trimming-knife, connecting means between said knife-bar and said movable trimming-knife for actuating the latter in a curvilinear path, and a throw-out device for disconnecting said knife-bar from said eccentric.
- 65 13. In a trimming mechanism for sewing machines provided with a needle-plate, the combination with a fixed trimming-knife associated with the needle-plate, of a co-operating movable trimming-knife, mechanical means above the needle-plate for actuating said knife in a curvilinear path, and means for normally pressing said movable knife sidewise against the fixed trimming-knife.
- 70 14. In a trimming mechanism for sewing machines provided with a needle-plate, the combination with a fixed trimming-knife associated with the needle-plate, of a knife-carrier pivoted to a stationary support at one side of the line of stitching and at a point distant therefrom, a movable trimming-knife connected with said knife-carrier at the other side of said line of stitching, and means for oscillating said knife-carrier.
- 75 Signed at Cleveland, in the county of Cuyahoga, and State of Ohio, this 17th day of June, A. D. 1911.
- 80 RALPH S. KELSO.
